Specification for Design.

Patented Aug. 27, 1912.

Application filed May 29, 1912. Serial No. 700,516. Term of patent 14 years.

To all whom it may concern:

Be it known that I, LOUIS HIENER, a citizen of the United States, residing at Wheeling, in the county of Ohio and State of West Virginia, have invented a new, original, and ornamental Design for Holders for Safety-Razors, of which the following is a specification, reference being had to the accompanying drawing, forming part thereof, in which—

Figure 1 is a top plan view of a safety

razor holder, showing my new design; Figs. 2, 3 and 4 are front, rear and end elevations, respectively, of the same; and Fig. 5 is a bottom plan view of the same.

I claim:

The ornamental design for a holder for safety razors, as shown.

LOUIS HIENER.
